BUTADIENE PRODUCTION

Robert J. Patterson, Bartlesville, Okla., assignor
to Phillips Petroleum Company, a corporation
of Delaware

Application January 11, 1943, Serial No. 472,043

1 Claim. (Cl. 260—680)

This invention relates to the production of butadiene by dehydrogenation of normal butane, normal butene or mixtures of normal butane and normal butene. More particularly, it relates to a method of preventing the undesirable accumulation of isobutylene in the feed due to the conventional recycle of unconverted or only partially converted C₄ hydrocarbons, and at the same time increasing the utilization of the original feed and the overall yield of butadiene based on the charge.

It is now well known that in the dehydrogenation of normal butane and butenes to butadiene, substantial amounts of isobutylene are formed as by-products and build up to an objectionable extent by the recycle of the C₄ hydrocarbons other than butadiene contained in the effluent. It has been proposed to prevent this objectionable building up of isobutylene in the system by removing isobutylene from the recycled C₄ hydrocarbons, namely butane and butene. One method is to effect this removal by selective absorption or selective polymerization of the isobutylene by sulfuric acid. Another method is to subject a portion of the recycle stream to non-destructive hydrogenation to convert the butenes to butanes, fractionate the resulting butane mixture to separate the normal butane from the isobutane, and recycle the normal butane to the dehydrogenation step. The latter method is specifically disclosed in the copending application of J. P. Jones, Serial No. 404,420, filed July 28, 1941. These procedures are not entirely satisfactory because C₄ hydrocarbon material is thereby lost from the system reducing the overall yield of butadiene based on the charge.

The principal object of the present invention is to provide an improved method of making butadiene by the dehydrogenation of normal butane or butene. Another object is to provide such a method wherein the accumulation of isobutylene as a result of the recycle is prevented. Still another object is to improve the yield of butadiene based on the original charge. Yet another object is to effect conversion of isobutylene which would normally be recycled into normal butene which is recycled instead. Numerous other objects will hereinafter appear.

The accompanying drawing portrays diagrammatically one arrangement of equipment which may be used in carrying out the process of the present invention.

In accordance with my invention the isobutylene formed in the dehydrogenation of normal butane or butene is isomerized to normal butene or butenes in manner known per se and the normal butene or butenes so formed is returned to the charge to the dehydrogenation step.

In one embodiment, my invention may be practiced by passing the recycle stream containing

small amounts of isobutylene to a separation zone where the isobutylene is separated from the normal butane or butene or mixture of normal butane and butene as by fractionation. The normal butane or butene is recycled to the dehydrogenation step. The isobutylene is passed through a thermal or catalytic isomerization zone where it is subjected to known conditions of treatment effecting conversion of a substantial proportion of the isobutylene to normal butene or butenes. The isomerization effluent may then be fractionated or otherwise treated to segregate the unchanged isobutylene from the normal butene. The unchanged isobutylene so separated may then be conveniently recycled to the isomerization step for further conversion. The normal butene or butenes derived from the isomerization effluent are passed to the dehydrogenation process in which the butadiene is formed.

In the isomerization step, any of the known methods of isomerizing isobutylene to normal butenes may be used, such as those set forth on pages 58 and 59 of Egloff et al., "Isomerization of pure hydrocarbons," 1942; in the copending application of Hillyer et al., Serial No. 427,830, filed January 22, 1942; in the paper of Egloff et al., J. A. C. S. 61, 3571-3580 (1939); in British Patent 496,676 and in U. S. Patents 2,216,284, 2,216,285, 2,217,252, 2,220,693 and 2,277,650. I prefer to operate under conditions such that isobutylene conversion to normal butene or butenes per pass is at least 30% and preferably 40% or 50% or higher, so that the butene content of the isomerization effluent contains normal butene in a proportion at least corresponding to these percentage figures. The equilibrium concentration of isobutylene at 300° C. is generally considered to be about equal to that of butene-1 plus butene-2 and decreases with rise in temperature, so that the higher temperatures, namely 300° C. or above, are preferred in order to favor a high conversion to normal butenes. Typical equilibrium concentrations of normal butene present in the equilibrium mixture with isobutylene at various temperatures are listed as follows:

Temperature, ° C.	Volume per cent normal butene
315	51
371	56
427	59
482	62
538	64
649	66
704	67

It is preferred to so operate that the butenes contained in the isomerization effluent comprise at least 50 per cent of normal butene. The selection of suitable isomerization conditions, in-

cluding catalyst, temperature, pressure and contact time, to effect the desired conversion in satisfactory yields is a matter well within the present-day skill of the art and need not be set forth in detail. It may be said, however, that frequently it is preferred to use a catalyst of phosphoric acid on a suitable adsorbent carrier. Furthermore, it is preferred to use conditions minimizing or preventing polymerization, cracking or other undesirable side reactions.

It is an advantage that the normal butene produced in the isomerization step comprises largely butene-2 which by reason of its boiling point may be readily separated from unconverted isobutylene and any butene-1 by simple fractional distillation. The unconverted isobutylene and the minor amount of butene-1 so separated may conveniently be recycled, without fractionation to effect separation between isobutylene and butene-1 to the isomerization step. Moreover, butene-2 is sometimes preferred as a feed to a dehydrogenation step for producing butadiene.

Referring to the accompanying drawing, a feed comprising or consisting essentially of normal butane or normal butenes, or a mixture of normal butane and at least one normal butene is introduced to the system via line 1 and passes through catalytic dehydrogenation unit 2 where a substantial proportion of butadiene is formed from the components of the feed.

Dehydrogenation unit 2 is not described in detail but may be of any known type, either single stage or, more usually, two-stage with or without intermediate treatment for concentration of butenes for feed to the second stage. Usually the first stage is so operated that the principal conversion is that of normal butane to normal butene, no or very little butadiene being formed in that step, and the butene-1 and butene-2 contained in the effluent are separated from other components and employed as feed to the second stage where the predominating reaction is conversion of normal butene to butadiene, although concomitant formation of small amounts of isobutylene and normal butane in the second stage is usually encountered.

Accordingly, construction and operation of dehydrogenation unit 2 are now well within the skill of the art. It will further be understood that while it is illustrated diagrammatically, the recycle need not be to the original feed stream where that is, as usual, normal butane, but that recycle of normal butane and of normal butene is usually to the first and second stages respectively.

The dehydrogenation effluent from the final stage passes via line 3 to butadiene separation unit 4 which is indicated diagrammatically and may be of any suitable type, employing known methods of selectively extracting butadiene, such as selective solvent extraction as by extractive distillation with furfural as a solvent, sulfone formation, azeotropic distillation, formation of cuprous chloride-butadiene complex, etc.

The butadiene-free stream leaves via line 5 and may pass thence via line 6 to isobutylene separation where isobutylene is separated or concentrated in any suitable manner, as for example by fractional distillation, solvent extraction, azeotropic distillation, sulfuric acid extraction followed by desorption, selective polymerization followed by depolymerization, etc. Unit 7 is indicated only diagrammatically because its construction and operation are well within the skill of the art. The butane leaves unit 7 via line 8

and is recycled via line 9. Usually this is mainly normal butane, no or only very little isobutane being formed in the dehydrogenation. Desirably the normal butenes, or at least the butene-2 content of the feed to unit 7 is removed in admixture with the butane.

The isobutylene, either substantially pure or in admixture with some or all of the butene-1 if desired, leaves unit 7 via line 10 and passes to isomerizer 11 where the isobutylene is converted to normal butene, usually mainly butene-2.

If desired, under appropriate circumstances, the effluent from butadiene separation unit 5 may partially or entirely by-pass the isobutylene separation unit 7 by means of line 12.

The effluent from isomerization unit 11 passes via line 13 for recycle to the dehydrogenation unit 2. Usually the conversion of isobutylene to normal butene by isomerization in unit 11 will be sufficiently extensive to keep the isobutylene in the system from pyramiding to an objectionable extent even where the entire effluent from isomerizer 11 is recycled to unit 2 without separation of unconverted isobutylene contained therein.

If desired, however, the effluent from isomerizer 11 may be passed via line 14 into fractionator 15 where unconverted isobutene, either essentially pure or in admixture with any butene-1 contained in the effluent from isomerizer 11, is removed as an overhead fraction via line 16 and recycled to isomerizer 11. The butene-2 content of the charge to fractionator 15 is separated as a bottom fraction and passed via line 17 to recycle to unit 2.

If desired, fractionator 15 may be partially or completely by-passed by means of line 13 depending upon the operating conditions encountered.

In an embodiment which is frequently preferred, the isobutylene separation may include the steps of treating the mixture of butene-1 and isobutylene, which is extremely difficult to resolve by ordinary fractional distillation, in such manner as to isomerize the butene-1 to butene-2 and then fractionating this isomerization effluent to separate the butene-2 so formed from isobutylene and unconverted butene-1. This insures substantially complete absence of butene-1 from the feed to unit 11. Such a modification may be practiced as illustrated in the drawing by passing the mixture of isobutylene and butene-1 leaving unit 7 via line 10 through line 18 to isomerization unit 19. The isomerization effluent leaving unit 19 is passed via line 20 to fractionation unit 21 which separates a fraction of butene-2 withdrawn via line 22 and a fraction of isobutylene nearly free from butene-1 withdrawn via line 23 and fed thereto by to isomerization unit 11. A similar step for isomerization of butene-1 to butene-2 may be employed in conjunction with fractionator 15 in order to facilitate separation of all normal butene from isobutylene in said fractionator.

It will be understood that while the drawing shows the recycle as a single stream passing via line 9 into unit 2, in practice where two-stage dehydrogenation of normal butane is involved, the recycle may be by way of two streams one being normal butane to the first stage and the other being normal butene recycled to the second stage, these being separated in any manner from one another. It will also be understood that the first stage effluent is most conveniently treated to separate a normal butene feed which

is fed to the second stage and a normal butane recycle stream which is recycled to the first stage. Furthermore, while the drawing shows unit 7 after unit 4, their position may be interchanged, or their functions combined into a single unit in which isobutylene, butadiene, normal butane and normal butene are separated from one another in any suitable manner.

I claim:

The process of making butadiene which comprises catalytically dehydrogenating an aliphatic C₄ hydrocarbon selected from the group consisting of normal butane and normal butenes under conditions such as to produce butadiene, separating butadiene from the dehydrogenation effluent, separating a fraction of isobutylene and butene-1 in admixture from the dehydrogenation effluent, recycling the butene-2 content of

dehydrogenation effluent to the dehydrogenation step, treating said fraction of isobutylene and butene-1 in such manner as to isomerize said butene-1 to butene-2, fractionally distilling the isomerization effluent to separate the butene-2 so produced from the isobutylene which is thus rendered substantially free from butene-1, treating the resulting isobutylene in such manner as to partially isomerize it to normal butene comprising a major proportion of butene-2, fractionally distilling the last-named isomerization effluent to separate it into a fraction containing the unconverted isobutylene and a fraction of butene-2, recycling said fraction of unconverted isobutylene to the last-named isomerization step, and feeding said last-named fraction of butene-2 to the dehydrogenation step.
